ABSTRACT OF THE DISCLOSURE

An impermeable membrane is attached to the sides of the paving laid upon a roadbed and extends downwardly and outwardly underneath the soil adjoining the paving to prevent water from seeping into the roadbed. The membrane can extend down underneath several feet of earth and, in some instances, depending upon the contour of the adjoining soil it may be desirable to lay drain conduits underneath the road surface to drain any water which may seep underneath the lower part of the membrane and under the paving.

BACKGROUND OF THE INVENTION

This invention relates to roadbed construction and to the control of water migration in soils adjoining the roadbeds. In accordance with another aspect, this invention relates to a method of preventing water from seeping into roadbeds from adjoining soil areas, especially planted areas, by placing an impermeable between the roadbed and the adjoining soil area. In accordance with a further aspect, this invention relates to roadway construction wherein an impermeable membrane is placed between the sides of paving and the roadbed upon which the paving is laid and adjoining soil which has a tendency to permit water to undermine the paving. In accordance with a further aspect, this invention relates to the placing of an impermeable membrane formed from polymeric materials or a polymeric fabric coated with asphalt which is placed between soil adjoining paving and underneath the soil a substantial distance away from the paving to prevent water from seeping into the roadbed and undermining the paving.

The problem of moisture infiltration under roadways has proved to be a severe one. Observation made during recent pavement repairs at service station and restaurant locations on a turnpike revealed that surface water from large planter areas and grass-covered islands with curbs is a major cause of pavement failure. Water from the planted areas seeps under the curbs and gutters and into the granular base. Freeze and thaw cycles plus heavy truck traffic result in pavement failure and costly repairs.

In accordance with the invention, it is proposed to install a water impervious membrane along the side walls and bottoms of soil areas, especially planted areas, adjoining paving along the inside walls and bottoms of the soil area to prevent water from weakening the road base.

Accordingly, an object of this invention is to provide a method for preventing water from seeping into roadbeds and undermining pavement laid thereon.

Another object of this invention is to provide improved road construction adjacent to a soil area having a tendency to permit water to drain under and undermine the paving whereby the seepage of water is minimized.

Another object of this invention is to provide a water impermeable membrane between roadbeds and adjoining soil areas.

Another object of this invention is to provide an impermeable water barrier between planted areas and adjoining roadways.

A further object of this invention is to provide relatively

2

inexpensive but effective water barriers between roadways and adjoining soil areas to prevent water seepage into the roadbed.

Other objects and aspects, as well as the several advantages of the invention, will be apparent to those skilled in the art upon reading this disclosure and the appended claims.

STATEMENT OF THE INVENTION

10 In accordance with the invention, an impermeable membrane is laid underneath the soil adjoining paving and alongside the roadbed and paving between the soil to prevent water from seeping into the roadbed from the adjoining soil area.

15 In accordance with one embodiment, the impermeable membrane is attached to the sides of the paving and extends downwardly several feet into the earth and then outwardly a substantial distance from the roadbed so as to prevent water from seeping into the roadbed and undermining the paving.

20 In accordance with another embodiment of the invention, drain conduits are provided in the soil area to permit carry-off of excess water and prevent buildup of water in the soil area which could sour the roots of plants that may be planted in a soil area adjoining the roadway.

25 The invention is applicable to single roadways to prevent water seepage from either or both sides of the road from adjoining soil into the roadbed or it can be used in multiple roadways having flat, raised, or depressed median strips comprised of soil which may be planted.

30 In accordance with presently preferred embodiments, the water impervious membrane is comprised of a polymeric film, preferably a thermoplastic polymeric film, or it can be a polymeric fabric coated with an asphalt.

35 DESCRIPTION OF THE PREFERRED EMBODIMENTS

As indicated above, the invention relates to methods and construction for preventing moisture from seeping into roadbeds upon which paving is laid. A liquid impervious membrane is used to prevent the liquid, especially water, from penetrating the roadbed and undermining the paving. The impervious membrane can be made of plastic film such as polyethylene, polypropylene, nylon, polyesters, and the like. The impervious membrane can also be made of fabrics such as those made of thermoplastic polymers such as polyethylene, polypropylene, nylon, polyesters, and the like. When employing a polymeric fabric, it is preferably impregnated with asphalt. The asphalt is preferably applied as a water emulsion. The asphalt can be dispersed in hydrocarbon such as kerosene or distillate.

The plastic films that can be employed ordinarily will be of a 3 to 25 mil thickness. The films can be oriented or unoriented polymeric films. The films can be prepared by any of the known techniques for the fabrication of films of desired thickness and sizes.

It is presently preferred to employ polymeric fabric materials since it is generally more pliable and more easily manipulated and fabricated in field operations. The fabric can be sewed in place during road construction to provide the proper fitting or form desired; instead of sewing, if desired, the membrane can be overlapped. When overlapping is used to join adjacent sections of membrane, an emulsified asphalt can be used to seal the sections together by overlapping the sections and applying the asphalt between the overlapped sections.

In some instances prior to applying an impervious membrane according to the invention to a roadbed, it may be desirable to seal the roadbed first with an asphalt emulsion. The sealing asphalt emulsion can be either an aqueous emulsion or a cutback petroleum emulsion. "Cutback" petroleum emulsion is asphalt emulsified in a hydrocar-

bon such as kerosene or fuel oil. Emulsifying agents such as cationic, anionic or nonionic can be used. Cationic agents are preferred because they appear to provide a stronger adherence to both the fabric and the soil.

In one embodiment of the invention, there is provided as a membrane for a roadway a laminate system consisting of a polyolefin, e.g., polypropylene, fabric impregnated with an asphalt-like material, e.g., asphalt. Also according to the invention, a layer of the fabric and a layer of film can be combined with an asphalt-like material. Thus, a film of polypropylene or polyethylene can be composited with a fabric of polypropylene or polyethylene, or any combination of polyolefins or other polymers or copolymers, fabric or film can be used. Substitution of fabric and/or film can be made upon mere routine testing of the particular material, its structure and the intended use. The now preferred fabric is a polypropylene fabric such as "Loktuft."

"Loktuft" is a nonwoven fabric of polypropylene fibers and is available from Renovah Spinning Mills, Trenton and Castor Avenues, Philadelphia, Pa. 19134. "Loktuft" is available in rolls of about six feet width and lengths of about 200 to 300 lineal feet. "Loktuft" has a weight of about four to six ounces per square yard, a tensile strength of the "warp" direction of 80-90 pounds and a tensile strength in the fill or woof direction of about 90-100 pounds. "Loktuft," we have found, will hold up to about four times as much asphalt material as will burlap mats, cotton fibers, woven cloth, etc.

The preferred film now is polyethylene since the combination of it with the above-described fabric has yielded desirable results.

The asphaltic material can be applied to the fabric by impregnation, painting, spraying or any other manner in which such materials are ordinarily applied. Preferably, the fabric is positioned in place and then sprayed with sufficient asphaltic material, for example, an asphalt emulsion, to embody the fabric into the asphalt.

The asphalts used in the preparation of the emulsion include any of those bituminous materials used heretofore and known in the prior art, such as natural asphalts or those derived from petroleum refining, for example, by steam refining and/or air blowing, and the like. Asphalts characterized by penetrations (ASTM D-5-51) from 0 to about 300 or even higher and preferably from about 40 to 300 and having softening points (ASTM D-36-26) in the range of 90 to 250° F., and preferably 100 to 150° F., represent suitable asphalts that can be employed.

The relative amounts of the various components of the asphalt emulsions can vary, but in general the asphalt is present in an amount in the range of 50 to 70, preferably 60 to 65 weight percent; the emulsifier is present in an amount in the range of 0.1 to 4, preferably 0.25 to 1; and water is present in the amount between 50 and 25, preferably 32-39 weight percent based on the total blend.

The asphalt emulsions employed can be prepared by any method known to those skilled in the art, for example, by preparing a soap solution comprising water, either soft or hard, and an emulsifying agent, either cationic, anionic, or nonionic. The soap solution is then mixed in a colloid mill or the like with the asphalt phase, the latter being preferably heated to reduce the viscosity. Usually the emulsifiers and any modifiers or promoters are dispersed in the water to form a soap solution which is then warmed to a temperature of 90 to 200° F., preferably 90 to 125° F. The asphalt can be heated to a temperature in the range of 150 to 350° F., preferably 250 to 300° F. The warm soap solution and hot asphalt are then proportioned to a colloid mill to emulsify the mixture during which milling the temperature of the mixture can be in the range of 100 to 210° F., preferably 150 to 200° F. The completed emulsion is then cooled to a temperature below 150° F. before being used or transferred to storage. The method of preparing an emulsion will have some effect on the properties thereof and the in-

tended application or utility of the emulsion will dictate which particular method one should use to get the desired properties.

The emulsifying agents employed to prepare the asphalt emulsion can be cationic, anionic, or nonionic, or combinations thereof.

Typical of the cationic emulsifying agents which can be used in the invention are salts of organic bases characterized by the presence of at least one basic nitrogen atom in the cationic portion and where the latter contains a long chain aliphatic hydrocarbon radical of at least 12 and as many as 24 carbon atoms, preferably a straight chain fatty aliphatic group. A particularly useful subclass of such cationic emulsifying agents are the tetra substituted quaternary ammonium compounds which are well known in the art for use in preparing cationic asphalt emulsions.

Typical of the nonionic emulsifying agents which can be used, and which are well known in the art, include those of the general formula:

where R is selected from the group consisting of hydrogen, aryl, and alkylaryl radicals; x, y and z are integers such that (1) when x is zero, y is also zero, and z is in the range of 6 to 11, inclusive, and said R is one of said aryl and alkylaryl radicals, and (2) when x and y are each greater than zero, the sum of x and z is in the range of 20 to 40, inclusive, and y is in the range of 40 to 60, inclusive.

Typical of the anionic emulsifying agents which can be used include the sulfonates, particularly and alkylaryl sulfonates such as n- or iso-p-octyl-phenoxy-poly(ethylene oxy) ethanol sodium sulfonates; and the sulfates, such as ammonium lauryl sulfate, all well known in the art.

These emulsions can be made so that they are stable for storage and transportation, yet will break rapidly when applied. Well known coagulating agents or electrolytes can be employed to aid in the breaking of the emulsion and applied to the surface to be treated.

In a preferred composition, the sealing asphalt emulsion can be an aqueous asphaltic emulsion which contains from 30-50 percent water by weight, the amount of water depending upon the type of soil in the roadbed. If the soil in the roadbed is highly permeable, the concentration of water in the asphaltic emulsion will be decreased. If a cutback petroleum asphalt emulsion is employed, the concentration of the petroleum dispersing agent can range from 10 to 15 percent by weight.

In actually carrying out the sealing of a roadbed with an asphaltic emulsion as defined above, after the sealing agent has been added and has cured for 12 to 24 hours the polymeric fabric is applied and it is coated with either an aqueous asphalt emulsion or a cutback petroleum asphalt emulsion. The aqueous emulsion can contain 30-35 weight percent water and can possibly be as high as 50 weight percent. The petroleum cutback emulsion usually has from 10 to 25 percent by weight petroleum oil and can be as high as 50 weight percent. After the fabric has been coated and allowed to cure for 12 to 24 hours, additional coats of asphalt can be applied. Usually the aqueous asphalt is used because it is easier to handle and cures faster.

In some instances it is desirable to add to the coats of asphalt applied to the polymeric fabric fillers with high surface areas such as asbestos, vermiculite, diatomaceous earth and petroleum coke. These fillers reduce the flow of asphalt and increase the resistance to impact. If the membrane should be exposed to the atmosphere, the filler provides resistance to weathering. If asbestos filler is used, the membrane will be subject to permeation by gases and vapors and impermeable to the flow of liquid. This is advantageous in cases where bubbles of gases and vapor appear under the surface of the membrane.

The impermeable membrane, according to the invention, preferably extends from grade elevation of the soil

and paving several feet into the earth and then outwardly a substantial distance away from the roadbed to prevent seeping of water from the adjoining soil area into the roadbed. In many installations, especially around service stations and other areas along interstate highways, the adjoining soil area contains a number of plants and the grade elevation of this soil area usually corresponds to the elevation of the curb or paving surface, whichever is higher. In most installations, the sides of the paving will be bounded by a curb and gutter and the planted area will abut against the curb and be at the same top elevation or grade elevation as the top of the curb. Generally, the membrane will be placed anywhere from about 12 inches to two or three feet below the top of the soil and top of the paving or curbing bounding the paving. The membrane will extend outwardly away from the roadbed a substantial distance, say 10 to 15 feet, that is, a substantial distance between other roadways or in the case of multiple roadways the membrane can extend from one roadway to the other beneath the soil median strip.

A better understanding of the invention will be attained upon reference to the accompanying drawings wherein:

FIG. 1 is a typical installation of an impermeable membrane between a roadway bounded by a curb and gutter and an adjoining planted soil area having the same top elevation as the curbing;

FIG. 2 is a typical installation for an impermeable membrane extending between two roadways with a depressed median between the two roads;

FIG. 3 is a typical installation for an impermeable membrane extending between two roadways having between the roads a raised median;

FIG. 4 is an installation for a depressed median between spaced roadways provided with a drain to remove excess water trapped between the roadways above the impermeable membrane;

FIG. 5 is another embodiment for multiple roadways provided with a depressed median between the roadways and a drain for removing water from the depressed median area away from the roadway system;

FIG. 6 is a schematic view of one type of drain that can be used for removal of water from a median area between roadways;

FIG. 7 is another embodiment for a median strip provided with drainage areas between plural roadways wherein a portion of the median is raised and the areas adjacent to the roadways are depressed to provide water flow and drain-off areas; and

FIG. 8 is another embodiment for a raised median between roadways wherein the water drainage from the raised median is onto the roadways adjacent the median strip.

Referring now to FIG. 1, the surface of the road for paving 10 is laid upon granular base 11 and earthen roadbed 12. The sides of the paving are bounded by a curb and gutter element 13. The adjoining soil area 14 contains tree 15 and grass and other plants. The grade elevation of the soil area corresponds to the grade elevation of curb 13.

Positioned between curb and gutter 13 and soil area 14 is a polymeric film or polymeric fabric coated with asphalt impermeable membrane 17. The membrane extends from the top of curb 13 downwardly into the earth approximately two feet and then extends outwardly away from granular base 11 and roadbed 12.

A perforated drainpipe which can be either metal or plastic 16 is provided for removing water drainage trapped in the soil above membrane 17 by way of pipe 16 to remove it from under the tree area out beyond the roadway system.

Referring to FIG. 2, there is illustrated road 20 and road 21 which can be a part of a multiple road system and positioned between roads 20 and 21 is a depressed median which can be planted, identified as 22. Approximately 12 inches below the surface of median 22 is im-

permeable membrane 23 which extends between roadway 20 and roadway 21. The ends of membrane 23 can extend up along the ends of road 21 or the paving portion. Roadway 21 is made up of a paving layer and a granular base 25. Similarly, roadway 20 is made up of paving 26 and granular base 27. The ends of membrane 23 can be fastened to the sides of paving 24 and 26 or, if preferred, can be laid upon the top of granular base 25 and granular base 27 and then formation of the paving 24 and 26 on top of the ends of the membrane. This will permit water from seeping under the roadbed and undermining the paving. It is presently preferred to extend the ends of the membrane up alongside the ends of the paving 24 and 26, terminating at the top of median 22. This embodiment does not include a water drain, but, as illustrated by the drawing, such is contemplated.

Referring to FIG. 3, roadway 28 and roadway 29 bound the raised median 30. Roadway 28 is made up of paving 31 and granular base 32, while roadway 29 is comprised of paving layer 33 and granular base 34.

Positioned approximately one foot below the surface of raised median 30 is membrane 35 which extends from roadway 28 to roadway 29. As described in connection with FIG. 2, the ends of the membrane can terminate parallel to the end of the pavement at the top of the paving and soil median or can extend beneath the paving layer and over the granular base layer as described in FIG. 2. Additionally, if desired, the drain can be provided when necessary.

In the above embodiments it has been found that polypropylene fabric coated with an asphalt emulsion provides a very effective water impermeable membrane. The polypropylene or other polymeric fabric that can be employed can be either a woven material, partially woven, or a non-woven fabric which can be needle punched or otherwise produced. A non-woven polypropylene mat is very effective as a water impermeable membrane when coated with a cationic emulsion of asphalt. The mat is made up of oriented polypropylene fibers randomly placed on a supporting scrim. The fibers are surface fused to one another to provide omnidirectional strength. The polypropylene fibers being a non-polar hydrocarbon are readily wetted by asphalt, thus imparting the strength of the mat to the asphalt.

Referring to FIG. 4, there is illustrated multiple roadways 36 and 37, bounding a depressed median 38 provided with a drain 39 positioned at an intermediate point in the depressed median. Positioned below the top of median 38 which is soil is impermeable membrane 40 which terminates along the edges of roadways 36 and 37. The end of membrane 40 corresponds to the top of roadways 36 and 37. The water drainage in the depressed median is withdrawn by way of drain 39 and removed by way of a natural bed stream illustrated by 41.

Referring to FIG. 5, roadways 42 and 43 bound a depressed median 44 which has beneath its surface at approximately one foot impermeable membrane 45 extending between roadways 42 and 43. Again, the ends of membrane 45 terminate along the edges of the roadways and at the tops of roadways 42 and 43. A drainpipe 46 extends from the top of depressed median 44 beneath the roadway and removes water to the far side of road 43 into a ditch 47. The top of water drain 46 can be provided with a suitable grate.

In FIG. 5, the water draw-off is similar to that of water draw-offs for streets. Either slotted or perforated iron covers can be used. The draw-offs can be positioned at intervals along the road. The waterflow from the draw-offs can be perpendicular to the roadways. These draw-offs pass underneath the roadways and discharge into a ditch or a ravine along the side of the road.

In FIG. 6, the bowl for the water draw-off extends only to the surface of the impermeable membrane. The membrane 48 extends from two roadways not shown. The 75 water bowl or drain 49 terminates at the interface of

membrane 48. The membrane is covered with soil 50. The outlet for water bowl 49 is covered with fine gravel or porous membrane to prevent objects from plugging the grate. The fine gravel is identified as 61.

Referring to FIG. 7, there is illustrated roadways 51 and 52 which bound an S-shaped raised median 53. There are depressed areas 54 and 55 adjacent to roadways 51 and 52, respectively. Water drains from the roadways and the crest of the raised median toward depressed areas 54 and 55. Disposed below median 53 and depressed areas 54 and 55 is a membrane 56. The depressed median areas 54 and 55 can be provided with drains as described above with respect to FIGS. 5 and 6. The same type of bowls for the water to enter can be used as those described in connection with FIGS. 5 and 6. Water can flow from the bowl into a conduit that extends underneath both roadbeds. The conduit can also carry rain water from a natural stream bed as illustrated in FIG. 4. The bowls in the various embodiments described can be connected to a conduit that runs parallel to the roadbed and eventually discharges into a conduit such as that shown in FIG. 4 or in FIGS. 5 and 6. The non-permeable membrane or film in all of the figures described above is attached to the roadbed and to the drainage bowls with an adhesive such as an asphalt or epoxy adhesive.

In a raised median such as that illustrated in FIG. 8 having roadways 57 and 58 bounding a raised median 59 having disposed below the median 59 an impermeable membrane 60, water flows from the raised median across the roadbed.

TYPICAL APPLICATION

In order to prevent shifting and erosion of the subsurface of a roadway (e.g., a concrete highway ribbon) the following construction is typical:

On each side of the concrete ribbon:

(a) Remove the earthen material from (each side of) the concrete ribbon, exposing the vertical edge of the pavement. Excavate so that there is a slope from the bottom of the vertical edge of the pavement downwardly to the drainage ditch which parallels the pavement. (The centerline of the bottom of the ditch in this example is about 4 feet below the level of the road and about 12 feet from the edge of the ribbon.)

(b) The sloping surface, prepared in (a), is covered with a non-woven polypropylene fabric (Loktuft (TM)). The fabric can be joined at its edges by such as sewing in order to make a continuous piece over the excavated surface. The fabric is placed so that its upper edge will be against the vertical surface of the pavement and its lower edge is adjacent the ditch. The in-place fabric is coated or saturated with an asphaltic material, preferably a cationic asphalt emulsion. The emulsion is applied in an amount of about $\frac{1}{2}$ gallon per square yard of fabric. Also, the fabric is sealed to the vertical edge of the pavement preferably with the same cationic asphalt emulsion. If desired, the fabric can be treated with the emulsion prior to laying it in place.

Immediately or after aging the emulsion up to 24 to 48 hours, the earthen material is replaced, covering the now water-impermeable membrane. The earthen material is contoured as desired between the roadway and the ditch.

The membrane will be covered by the earthen material usually at a depth of six inches to about four feet, depending upon the contour used.

Water which gets into this earthen fill, either from rain, drainage from the roadway, etc., and penetrates this fill will not penetrate the membrane, but will flow thereabove and ultimately into the bar or drainage ditch for disposal. In this manner, water is prevented from getting beneath

the pavement which would result in shifting and erosion of this subsurface with ultimate roadway failure.

We claim:

1. A method for preventing moisture from seeping from adjoining earthen material into a roadbed upon which paving is laid and where the earthen material and paving have substantially the same grade elevation which method comprises the steps of:

excavating said adjoining earthen material up to a depth below grade elevation sufficient to promote growth of plants upon replacement of the excavated earthen material along the edge of said roadbed so as to expose the vertical edge of said paving, said excavation extending outwardly a substantial distance away from said roadbed and forming a trench along said roadbed,

covering said trench remaining after excavation along said roadbed with a plastic membrane which extends from the top of said paving downwardly to the bottom of the trench and outwardly away from the roadbed said substantial distance, and

filling said membrane covered trench with earthen material so that upon replacement of the excavated earthen material the grade elevation of the earthen material and paving are substantially the same.

2. A method according to claim 1 wherein the trench after excavation is covered with a membrane formed by coating said trench with an asphalt emulsion to seal the trench walls, allowing said asphalt emulsion coat to dry, applying a polymeric fabric to the asphalt coated trench, and applying an asphalt emulsion to the polymeric fabric to form said membrane prior to filling said trench with earthen material.

3. A method according to claim 1 wherein the edge of said paving is bounded by a curb and gutter and the grade elevation of said earthen material adjoining said curb is essentially the same as the top of said curb and further wherein said trench is sealed by application of an asphalt emulsion before applying said plastic membrane.

4. A method according to claim 1 wherein said plastic membrane is a polymeric film formed from polyethylene, polypropylene, nylon, and polyesters or a fabric material formed from at least one of the same polymers, which fabric is coated with asphalt, and said earthen material is excavated up to a depth of about 4 feet below grade elevation.

5. A method according to claim 1 wherein said earthen material is a planted area and a drain is placed in the bottom of said trench to remove water trapped by the membrane disposed below the surface of the earthen material and which drain carries the water away from the earthen material and prevents collection of water above the membrane.
